UNITED STATES PATENT OFFICE

2,063,012

ROLLER ROCK BIT

Alfred C. Catland, Alhambra, Calif., assignor to
 Globe Oil Tools Company, Los Nietos, Calif., a
 corporation of California

Application October 14, 1935, Serial No. 44,852

11 Claims. (Cl. 255—71)

This invention relates to a well drilling tool and relates more particularly to a rock bit for use in the rotary method of well drilling. A general object of this invention is to provide a 5 roller rock bit that is rapid and efficient in operation and that is simple and sturdy in construction.

Another object of this invention is to provide a well bit that embodies a simple one piece bearing member or spider rotatably supporting the 10 several roller cutters, which spider is removably attached to the shank in a simple dependable manner.

Another object of the invention is to provide 15 a roller well bit embodying a choke nipple for discharging the circulation fluid that is removably secured to the shank in a manner so that it forms a means for assisting in securing the cutter carrying spider to the shank.

Another object of this invention is to provide 20 a rock bit embodying inner roller cutters and outer roller cutters mounted and related to be particularly rapid and efficient in their cutting action.

A further object of this invention is to provide 25 a roller rock bit that may be very easily and quickly repaired and reconditioned when the cutters, etc. become worn.

The various objects and features of my invention will be fully understood from the following 30 detailed description of a typical preferred form and application of my invention, throughout which description reference is made to the accompanying drawing, in which:

Fig. 1 is a side elevation of the bit provided 35 by the present invention with a portion broken away to appear in vertical cross section. Fig. 2 is a vertical detailed sectional view of the bit taken in a plane at right angles to the plane of 40 sectioning of Fig. 1. Fig. 3 is a bottom elevation of the shank with the cutter mounting member removed. Fig. 4 is a bottom elevation of the bit and Fig. 5 is a bottom elevation of the cutter carrying member or spider with the cutters removed.

The well drilling bit provided by the present 45 invention includes, generally, a body or shank 10, a removable bearing member or spider 11 on the shank 10, inner cutters 12 rotatably supported by the spider 11 and outer cutters 13 rotatably supported by the spider 11.

The body or shank 10 of the bit is adapted to be connected with the lower end of a drilling string. The shank 10 is a simple integral member having means at its upper end for connect-

ing with the drilling string and having its lower end shaped and formed to carry the spider 11, etc. In the typical form of the invention illustrated in the drawing the shank 10 is cylindrical in its general configuration and is provided at its upper end with a tapered screw threaded pin 14 for facilitating its connection with a drilling string. The lower face 15 of the shank 10 is flat and is preferably substantially horizontal. In accordance with the invention the shank 10 is 10 provided with downwardly extending projections or legs. There are two substantially diametrical 15 opposite legs 16 projecting from the lower end face 15 adjacent the periphery of the shank. The legs 16 may project outwardly as well as 15 downwardly from the shank 10 and their inner sides 17 are inclined downwardly and outwardly. The shank 10 is provided with a third leg 18 projecting downwardly from its lower end adjacent its periphery. The inner side or surface 19 of 20 the leg 18 is inclined downwardly and inwardly relative to the central vertical axis of the bit. The leg 18 is integral with the shank 10 and is spaced approximately 90° from the legs 16.

The bearing member or spider 11 for carrying 25 the cutters 12 and 13 is preferably a simple one-piece member as illustrated throughout the drawing. The spider 11 includes an inner part or hub 20 having a flat upper surface 21 for seating or bearing against the lower face 15 of the shank. The hub 20 is preferably comparatively thick 30 vertically and is provided with a vertical opening 22. The spider 11 includes projecting parts or arms for carrying the cutters 12 and 13. Two arms 23 project from the lower portion of the 35 spider hub 20 and lie in a plane substantially diametric of the central vertical axis of the shank 10. The major portions of the arms 23 are cylindrical to rotatably carry the cutters 13 and their longitudinal axes are inclined downwardly and inwardly with respect to the longitudinal axis of the shank. Recesses 24 are provided in the inner sides 17 of the legs 16. The recesses 24 extend upwardly from adjacent the lower ends of the legs 16 and have flat parallel 40 side walls and concaved upper walls. The arms 23 of the spider 11 have reduced outer end portions 25 which enter the recesses 24 and bear upwardly against their upper walls. The extreme outer ends of the arms 23 are adapted to bear against the bottom walls of the recesses 45 24. The reduced portions 25 of the arms 23 provide the arms with annular outwardly facing shoulders 26 which are spaced from the inner sides 17 of the legs 16.

The arms 23 of the spider 11 have reduced outer end portions 25 which enter the recesses 24 and bear upwardly against their upper walls. The extreme outer ends of the arms 23 are adapted to bear against the bottom walls of the recesses 50 24. The reduced portions 25 of the arms 23 provide the arms with annular outwardly facing shoulders 26 which are spaced from the inner sides 17 of the legs 16.

The spider 11 has a third arm 27 for carrying the inner cutters 12. The arm 27 projects downwardly and outwardly from the lower portion of the hub 20 and is cylindrical to rotatably carry the inner cutters 12. In the preferred construction the arm 27 is inclined downwardly and outwardly relative to the central vertical axis of the shank 10. The cutter carrying arm 27 is spaced approximately 10° from the arms 23 and its outer end is adapted to cooperate with the shank leg 18. A groove or recess 28 is provided in the inner surface 19 of the leg 18 to receive a reduced end portion 29 of the arm 27. The recess 28 may be similar in shape 15 to the recesses 24. The extreme outer end of the arm 27 is adapted to bear against the bottom or outer wall of the recess 28 and the reduced portion 29 is adapted to bear upwardly against the upper wall of the recess. The reduced end portion 29 provides the arm 27 with an outwardly facing annular shoulder 30 which is spaced from the leg 18.

The invention provides novel effective means for tying the arms 23 to the legs 16 and the arm 27 to the leg 18 and for assisting in removably securing the spider 11 to the shank 10. Central longitudinal openings 31 extend through the arms 23 from one end to the other and a similar opening 32 extends through the arm 27. Screws 33 are passed into the openings 31 from their inner ends and are threaded into openings 34 in the legs 16. The heads 35 of the screws 33 are received in counter bores in the inner ends of the openings 31. Cotter keys 36 extend into the counter bores of the openings 31 to prevent unthreading of the screws 33. A screw 37 is passed into the opening 32 from its inner end and is threaded into an opening 38 in the leg 18. The head 39 of the screw 37 is received in a counter bore in the inner end of the opening 32. The screw 37 is retained against loosening and displacement in the manner to be hereinafter described. The screws 33 effectively tie the arms 23 to the legs 16 while the screw 37 effectively ties the arm 27 to the leg 18. The positioning or arrangement of the screws 33 and 37 is important. The screws 33 and 37 being arranged with their heads 35 and 39 in counter bores in the spider 11 do not necessitate the formation 50 of counter bores in the legs 16 or 18 and, therefore, do not necessitate the weakening of the legs. A second advantage resulting from the above described arrangement of the screws 33 and 37 is that the heads 35 and 39 of the screws 55 and the counter bores receiving the heads are not worn away or destroyed to make the removal of the screws difficult in the event that the bit is worn excessively under gauge.

The inner cutters 12 are provided to act on 60 the central or inner portion of the bottom wall of the well bore. The inner cutters 12 are rotatably supported on the spider arm 27 to project downwardly beyond the lower end of the spider and the leg 18. In the particular form of the 65 invention illustrated in the drawing there are two inner cutters mounted on the arm 27 in side by side relation. The innermost cutter 12 is frusto-conical having axially extending cutting teeth 40 inclined with respect to its axis of 70 rotation. The outer cutter 12 may be cylindrical in its general configuration having axially extending teeth 41 equidistant from its axis of rotation. The openings of the cutters 12 have counter bores 42 which carry anti-friction bearings 43 for supporting the cutters on the arm

27. A recess 44 is provided in the outer end of the innermost cutter 12 to receive a spacer or thrust washer 45. A recess 46 is provided in the outer end of the outer cutter 12 to receive a thrust washer 47. The thrust washer 47 bears 5 between the inner surface 19 of the leg 18 and the annular shoulder 30 of the arm 27. The thrust washer 47 has shouldered engagement with the leg 18 at 48 which holds it against rotation on the arm 27. During rotation of the 10 bit the frusto-conical cutter 12 operates to leave a central substantially conical projection on the bottom of the well bore and the cooperation of the cutter with this raised portion of formation assists in centering and stabilizing the bit. 15

The outer cutters 13 are provided to cut or drill the outer portion of the well bore and ream the bore to size. An outer roller cutter 13 is rotatably supported on each arm 23 of the spider 11. The outer cutters 13 are frusto conical and 20 are arranged with their small ends innermost. Counter bores 50 are provided in the openings of the cutters 13 to carry anti-friction roller bearings 51 which support the cutters on the arms 23. Recesses 52 are provided in the outer ends 25 of the cutters 13 to receive thrust washers 53. The thrust washers 53 are arranged on the arms 23 to bear between the shoulders 26 and the inner sides 17 of the legs 16. The thrust washers 53 have shouldered engagement with the legs 30 16 at 54, which engagement holds the washers against turning.

The outer cutters 13 have axially extending teeth 55 on their peripheries which project downwardly and outwardly from beyond the lower ends of the legs 16 to act on the earth formation. The outer corners of the teeth 55 are bevelled away at 56 to properly cut or ream the side wall of the well bore. The frusto-conical outer cutters 13 mounted to rotate about downwardly and inwardly inclined axes have their cutting parts substantially horizontal as they come into engagement with the formation at the bottom wall of the bore and have their bevelled ends 56 substantially vertical as they act on the 45 formation. In practice the inner and outer cutters 12 and 13 are mounted and proportioned to overlap in their action on the formation at the bottom of the well bore. 40

The invention includes means for handling the 50 circulation fluid to fully flush the cutters and to materially assist in the drilling action. A vertical socket 49 is provided in the pin 14 of the shank 10 and is adapted to communicate with the lower end of the fluid passage in the drilling string. Ports 57 are provided in the shank 10 to extend downwardly from the socket 49 and discharge from the lower face 15 at points where the circulation fluid effectively flushes the cutters 12 and 13. A vertical port 58 of comparatively large diameter extends downwardly from the lower end of the socket 49 to the face 15. A replaceable wear taking flow nipple 59 is threaded in the lower portion of the port 58 and projects downwardly from the face 15. The 65 nipple 59 projects into the spider opening 22 with substantial clearance. A nozzle member or choke 60 is arranged in the opening 22 to surround the nipple 59. The nipple 59 arranged with a portion in the port 58 and a portion in the choke 60 projects the shank 10 and the choke 60 against the abrasive action of the solid matter in the circulation fluid. The choke 60 projects downwardly so that its lower end is comparatively close to the bottom of the well bore. The choke 70 75

60 is provided with a fluid discharge opening 61 in the form of a slot elongated radially with respect to the central vertical axis of the bit. The fluid discharging from the opening 61 adjacent to the bottom wall of the well bore is particularly effective in eroding or disintegrating the formation. As the opening 61 is elongated radially in horizontal cross section the fluid is discharged in a manner to have a sweeping action as it moves across the bottom of the well bore.

10 The invention provides effective means for removably securing the choke 60 to the shank 10. Ears or flanges 62 are provided on the choke 60 and are adapted to bear upwardly against the 15 lower face 21 of the spider hub 20. Screws 63 are passed upwardly through openings 64 in the flanges 62 and openings 65 in the spider hub 20 to thread into openings 66 in the lower end of the shank 10. The heads of the screws 63 are preferably countersunk in the lower ends of the openings 64. Cotter keys 67 project into the counter bores of the openings 64 to prevent unthreading of the screws 63. The screws 63 clamp the flanges of the nipple 60 upwardly against the spider 11 and 25 tightly clamp the upper surface 21 of the spider against the lower face 15 of the shank 10. The choke 60 thus acts as a securing member or medium for attaching the spider 11 to the shank 10. The choke 60 is proportioned to project in front 30 of and partially cover the inner end of the opening 32 so that it prevents loss or displacement of the screw 37. Accordingly, the choke 60 also acts as a lock member to prevent loss of the screw 37.

35 In operation of the bit the shank 10 is attached to the lower end of a drilling string and the bit is rotated and fed downwardly in the well in the usual manner. The inner cutters 12 act on and cut away the formation at the inner or central portion of the well. The circulation fluid under pressure discharging from the choke opening 61 impinges downwardly against the formation adjacent to the center of the bore. The fluid may erode the formation and thus assist the cutters 12 in their cutting action. The fluid discharged from 40 the ports 57 fully flushes the cutters 12 and 13. The conical cutter 12 rotatably supported on the inclined arm 21 leaves a centrally disposed substantially conical piece of projecting earth formation and its engagement with this centering protection stabilizes the bit. The outer roller cutters 45 13 act on the outer portion of the well bore and cut the bore to size. The cutters 12 and 13 are mounted for free rotating and are dependably fitted on their mountings. The screws 33 and 37 50 tie together the legs of the shank 10 and the arms of the spider 11 to materially strengthen the bit construction. The choke 60 operates to hold the spider upwardly against the lower face 15 of the shank 10 and serves to prevent displacement of 55 the screw 37. When the cutters become worn the spider 11 may be easily and quickly removed from the shank 10 to permit the replacement of the cutters, etc. The flow nipple 59 may be replaced when worn. The choke 60 connected with the 60 shank 10 by the screws 63 dependably secures the spider to the shank and is readily removable for replacement, etc.

Having described only a typical preferred form and application of my invention, I do not wish to be limited or restricted to the specific details herein set forth, but wish to reserve to myself any variations or modifications that may appear to those skilled in the art or fall within the scope of the following claims.

75 Having described my invention, I claim:

1. A well bit including a shank, a spider bearing against the lower end of the shank, there being a fluid passage in the shank, a fluid discharge member communicating with the passage and engaging against the spider, and a plurality of independent means securing the member to the shank at points spaced from the passage and urging the member against the spider to clamp the spider to the shank. 5

2. A well bit including a shank, a spider bearing against the lower end of the shank, there being a fluid passage in the shank, a fluid discharge member communicating with the passage and engaging against the spider, and screws spaced from the passage and attaching the member to 10 the shank and forcing the member upwardly against the spider to secure the spider to the shank. 15

3. A well drilling bit including a shank having a fluid passage, cutters, a spider carrying the cutters and bearing upwardly against the lower end of the shank, the spider having a fluid discharge opening, a fluid discharge member extending into the opening to receive fluid from the passage and engaging upwardly against the spider, a tubular 20 wear taking nipple threaded in the passage and extending into the said fluid discharge member; and means attaching the member to the shank and holding the spider upwardly against the shank. 25

4. A well bit including a shank having projecting legs, a member at the lower end of the shank, the member comprising arms projecting outwardly toward the legs, cutters rotatably supported by the arms, there being openings in the 30 arms, and screws entered in the openings from their inner ends and threaded in openings in the legs to tie together the arms and legs. 35

5. A well bit including a shank having a downwardly projecting leg, a member at the lower end 40 of the shank provided with an arm projecting outwardly to the leg, there being a longitudinal opening in the arm, a cutter rotatably supported by the arm, and a screw introduced in said opening from its inner end and threaded into an 45 opening in the leg to connect the arm and leg.

6. A well bit including a shank, a spider bearing against the lower end of the shank, there being a fluid passage in the shank, a fluid discharge member communicating with the passage and 50 engaging against the spider, a wear taking nipple having an end portion in the passage and its opposite end portion in the discharge member, and means securing the member to the shank and urging the member against the spider to clamp 55 the spider to the shank.

7. A well bit including a shank having a fluid passage, a leg projecting from the lower end of the shank, a spider at the lower end of the shank having an arm projecting outwardly to the leg, 60 a cutter rotatably supported by the arm, a fluid discharge member communicating with the passage and engaging upwardly against the spider, means securing the member to the shank and forcing the member upwardly against the spider 65 to clamp the spider to the shank, there being an opening in the arm, and a screw entered in the opening from its inner end and threaded into the leg to tie the arm to the leg.

8. A well bit including a shank having a fluid 70 passage, a leg projecting from the lower end of the shank, a spider at the lower end of the shank having an arm projecting outwardly to the leg, a cutter rotatably supported by the arm, a fluid discharge member communicating with the pas- 75

5 sage and engaging upwardly against the spider, means securing the member to the shank and forcing the member upwardly against the spider to clamp the spider to the shank, there being an opening in the arm having its inner end adjacent the discharge member, and a screw entered in said opening from its inner end and threaded into the leg to tie the arm to the leg, the discharge member extending across the inner end 10 of the opening to prevent unthreading of the screw.

9. A well bit including a shank having a fluid 15 passage, a leg projecting from the lower end of the shank, a spider at the lower end of the shank having an arm projecting outwardly to the leg, a cutter rotatably supported by the arm, a fluid discharge member communicating with the passage and engaging upwardly against the spider, means securing the member to the shank and 20 forcing the member upwardly against the spider to clamp the spider to the shank, said means including a screw engaging the discharge member and threaded into the shank, there being a longitudinal opening in the arm, and a screw entered in the inner end of the opening and threaded in the leg to tie the arm and leg together, the discharge member being positioned at 25 the inner end of the opening to prevent unthreading of the last named screw.

10. A well bit including, a shank, roller cutters rotatably carried by the shank to act on the formation at circumferentially spaced points to maintain the well bore to gauge, a member 5 removably attached to the shank, and an inner roller cutter carried by the member to act on the formation within the path of the outer cutters, there being a fluid passage in the shank, the member having a fluid carrying port communicating with and receiving fluid from the passage, 10 the walls of the port acting to confine the fluid and being formed to provide a discharge end of elongate cross section discharging the fluid downwardly adjacent the bottom of the bore.

11. A well bit including, a shank, roller cutters 15 rotatably carried by the shank to act on the formation at circumferentially spaced points to maintain the well bore to gauge, a member removably attached to the shank, and an inner roller cutter carried by the member to act on the 20 formation within the path of the outer cutters, there being a fluid passage in the shank, the member having a main port receiving fluid from the passage and discharging it downwardly 25 against the formation at the bottom of the bore and having reduced ports discharging streams of fluid against the several cutters.

ALFRED C. CATLAND.
